CLOCK OR SIMILAR ARTICLE

Morris Riba, New York, N. Y.

Application November 16, 1954, Serial No. 33,115

Term of patent 7 years

(Cl. D42—7)

To all whom it may concern:

Be it known that I, Morris Riba, a resident of the city of New York, in the county of New York, State of New York, have invented a new, original, and ornamental Design for a Clock or Similar Article, of which the following is a specification, reference being had to the accompanying drawing, forming a part hereof.

Fig. 1 is a front elevation of a clock embodying my new design.

Fig. 2 is an edge elevation thereof taken in the direction of the arrow 2 in Fig. 1.

Fig. 3 is a fragmentary cross-section thereof taken along the line 3—3 of Fig. 1.

I claim:

The ornamental design for a clock or similar article, as shown.
